Gas & Gasoline burner
to Wm. Crossman

No 545 Fig 2

Fig 1

Design for a parlor stove.
Patented Sept. 1, 1883.
Antecedents Dec. 13, 1882.

Fig 3

Des. 545

James H. Conklin, of New York, N. Y.

Assignor to

William T. Breson, of Philadelphia, Pa.

Letters Patent No. 545. Dated Feb 1st 1853,

Ante dated Dec. 13th 1852.

The schedule referred to in these Letters Patent and making part of the same

To all whom it may concern:

Be it known that I, James H. Conklin, of the City
of New York, in the County of New York, and State of New York, have invented or produced

a new and original design for a Parlor Stove, and I do hereby declare that the following is a full and exact description of the same.

Fig. 1. Represents the bottom plate of a peculiar form as represented in the drawing, the outer edge is ornamented with a series of scroll & flower work as represented at a, a, a, a, within which is a series of scalloped work running around from one edge of the draft door around the plate to the other edge of the draft door as represented at b, b, b, b, b.

Fig. 2. Represents the side plate and is also used for a front and back plate, it is of a peculiar form as represented in the drawing. It is ornamented with a scroll on either side which when the sides front and back are put together forms chambers for inlets of air to be heated and said scrolls are ornamented with flower work as at C, C, the lower portion of the plate is also ornamented in the centre with an oblong octagonal panel ornamented as at D, D, and having in the centre a lattice work intended to allow the entry of air after having been heated in the chambers as at E, E, the upper portion of the plate is a section of a cylinder having at the base a bead square as at F, F, and on the edge a bead ledging intended to cover the joints of the next plate as at G, the general surface being indented with diamond work as at F, F, and the centre a panel of a peculiar form as at I, the top of this plate is flared in an ogee form to receive the top plate as at J, J.

Fig. 3. Represents the top plate and is ornamented with a series of scroll and flower work as represented in the drawing having a hole in the centre to be covered by.

Fig. 4. Represents the cover and ornamented with a series of scroll and spear work as at H, H, —

I do not claim the peculiar form of this stove or any of the ornaments separately, but

What I do claim and desire to secure by Letters Patent is the combination and arrangement of the ornamental forms and figures represented in the accompanying drawings and forming together an ornamental design for a parlor stove.
